DESIGN FOR A WALL BOX

Melvin J. Binks, River Forest, Ill., assignor to J. H. Keeney & Co., Inc., Chicago, Ill., a corporation of Illinois

Application April 13, 1940, Serial No. 91,647

Term of patent 3½ years

To all whom it may concern:

Be it known that I, Melvin J. Binks, a citizen of the United States, residing at River Forest, in the county of Cook and State of Illinois, have invented a new, original, and ornamental Design for a Wall Box, of which the following is a specification, reference being had to the accompanying drawing, forming part thereof.

In the drawing:

Fig. 1 is a front elevational view of a wall box showing my new design.

Fig. 2 is a side elevational view of the wall box shown in Fig. 1.

Fig. 3 is a top plan view of the wall box shown in Fig. 1.

I claim:

The ornamental design for a wall box, substantially as shown.

MELVIN J. BINKS.
